ATTORNEY

UNITED STATES PATENT OFFICE.

FLORIS GOUBERT, OF PARIS, FRANCE.

PRESS STUD.

1,407,854.

Specification of Letters Patent. Patented Feb. 28, 1922.

Application filed September 3, 1921. Serial No. 498,299.

To all whom it may concern:

Be it known that I, FLORIS GOUBERT, citizen of the Republic of France, and resident of Paris, France, (post-office address 20 Rue 5 du Faubourg St. Martin,) have invented a new and useful Press Stud, (for which I have filed an application in France July 5, 1918,) which improvements are fully set forth in the following specification.

10 The present invention relates to a press-stud represented for example on the annexed drawing.

Figure 1 is a face view of the female part of the press-stud.

15 Figure 2 is a transverse section on line A—A of Figure 1.

Figure 3 is a view of the spring alone.

Figures 4, 5 and 6 represent a modification. The essential characteristic of the invention 20 consists in combining the cup-shaped female part of a press-stud with the spring *a* (Figure 3) so shaped as to contribute to the solidity of the connection between the male and female parts when these are joined.

25 The spring is secured at *b* by means of a finger stamped out of the metal plate forming the female part and turned down. The branches *b' b'* of the spring properly bent are made to enter the notches cut laterally 30 in the base of the up turned flap *c* of the

plate. This disposition is clearly shown Figure 2.

If the upturned flap, instead of being single as per Figures 1, 2, 3, is double as in Figures 4-5-6 the spring slightly modified 35 enters the notches formed in the bases of the upturned flaps *c', c'* (see Fig. 5); and is maintained in position by means of the finger *b*.

It is understood that the shape of the 40 spring may vary as the only essential feature is the means for fixing the spring in the cup-shaped female part of the press-stud.

What I claim is:

A fastener, comprising a cup-shaped 45 female member having an upstanding flap provided with a pair of opposite notches; a spring mounted in said member and having a part disposed against the rim thereof and having other parts engaged in said notches; 50 and a finger on said member overlying the first-named part of the spring to secure the latter in place.

In testimony whereof I have signed this specification in the presence of two subscribing 55 witnesses.

FLORIS GOUBERT.

Witnesses:

FERNAND DUPOUR,
CHARLES LEON LOISE.
